C. L. RAYFIELD

OIL BURNER

Filed Jan. 22, 1926

UNITED STATES PATENT OFFICE.

CHARLES L. RAYFIELD, OF CHICAGO, ILLINOIS, ASSIGNOR TO RAYFIELD MANUFACTURING COMPANY, A CORPORATION OF ILLINOIS.

OIL BURNER.

Application filed January 22, 1926. Serial No. 82,909.

This invention relates to an oil burner and more particularly to means for providing heated air for the combustion of the oil.

In a pressure type of oil burner, considerable heat is always generated in compressing the air used in conveying the oil, but this heat has hitherto been dissipated and wasted.

It is an object of this invention to provide an oil burner in which provision is made for utilizing the heat so generated to raise the temperature of the air used in combustion and thus obtain a greater efficiency of combustion.

Other and further important objects of the invention will hereinafter appear.

Fig. 1 is a front elevational view, with parts broken away, of an oil burner embodying the principles of my invention.

Fig. 2 is an end elevational view of the same, including a fragmentary view of a furnace with which the oil burner is used.

The reference numeral 1 indicates a movable supporting platform on which is mounted the oil burner 2 embodying the principles of my invention. Said oil burner 2 includes a motor 3 and suitable piping, valves, filters, oil pump, air compressor, and the like, all represented by the numeral 4 but not forming a direct part of this invention. Said motor 3 and mechanism 4 are housed within a closed casing 5 provided with apertures 6 adjacent the motor end. A fan 7 is mounted directly on the motor shaft 8 in such a position as to draw air through the apertures 6 and circulate said air in the direction indicated by the arrows against the mechanism 4 and especially around the air compressor. As the

air compressor during operation becomes heated, the circulating air will absorb this heat and in turn will be raised to a comparatively high temperature. The air is then discharged from the casing 4 through a combustion nozzle 9 along with the oil, which is delivered through a smaller, inside tubing 12, preferably in the form of a spray. The air and oil mixture is discharged directly into a furnace 10 through a door 11 in said furnace.

The added heat which the air absorbs from the air compressor aids greatly in the efficiency of the combustion of the oil and it also serves to cool the compressor and prevent the moving mechanism from overheating.

I am aware that many changes of detail may be made without departing from the principles of this invention, and I therefore do not purpose limiting the patent granted otherwise than necessitated by the prior art.

I claim as my invention:

1. In combination in an oil burner a housing having openings in its wall, oil pumping mechanism in said housing, an air compressor in said housing, means for sucking air into said housing through said openings and for circulating it around said compressor to cause it to be preheated by the heat given off by said compressor, a nozzle connected to said housing into which oil from said mechanism is discharged and into which said preheated air is discharged, and an oil line connected to said pumping mechanism and arranged so as to receive heat from the heated air delivered to said nozzle.

2. In combination in an oil burner a housing having openings in its wall, oil pumping mechanism in said housing, an air compressor in said housing, means for sucking air into said housing through said openings and for circulating it around said compressor to cause it to be preheated by the heat given off by said compressor, a nozzle connected to said housing into which oil from said mechanism is discharged and into which said preheated air is discharged, said nozzle comprising a tube connected to said housing at one end and having its other end provided with a discharge orifice and an oil line connected to said pumping mechanism and extending into said tube so as to receive heat from the heated air delivered to said nozzle.

3. In combination in an oil burner a housing having an apertured wall, a motor, a drive shaft driven by said motor and extending into said housing, air compressing

mechanism, oil pumping mechanism, both of said mechanisms being disposed in said housing and being driven by said shaft, and a fan positioned between said motor and

5 said mechanisms and actuated by said shaft, said fan being driven by said motor shaft to suck air through the apertures in said

wall and to circulate said air about said mechanisms to cause it to absorb some of the heat given off by said compressing mechanism. 10

In testimony whereof I have hereunto subscribed my name.

CHARLES L. RAYFIELD.
